UNITED STATES PATENT OFFICE.

THOMAS SPAULDING, OF LOS ANGELES, CALIFORNIA.

BEDCLOTHES-SUPPORT FOR FOLDING BEDS.

1,214,090.

Specification of Letters Patent. Patented Jan. 30, 1917.

Application filed October 18, 1915. Serial No. 56,644.

To all whom it may concern:

Be it known that I, THOMAS SPAULDING, a citizen of the United States, residing at Los Angeles, in the county of Los Angeles 5 and State of California, have invented new and useful Improvements in Bedclothes-Supports for Folding Beds, of which the following is a specification.

This invention relates to a bed clothes 10 support for folding beds.

It is the object of this invention to provide a device for supporting the bed clothes of vertically swinging folding beds when the latter are in their upright position and by 15 means of which the various articles of bed clothing may be held in separated relation to each other so as to effect ventilation thereof.

Another object is to provide a device of 20 the above character which can be readily applied to the ordinary vertically swung folding beds and which is simple in construction and easily operated.

A further object is to provide means by 25 which the bed clothes support will serve to hold the bed clothing at the foot of the bed against displacement when the bed is in its horizontal position.

Another object is to provide a locking 30 means whereby the foot portions of the various articles of bed clothing may be placed in spaced relation while the bed is in its horizontal position and maintained in such 35 spaced relation while the bed is being moved from its horizontal to its vertical position so that when the bed is folded into a recess where the bed clothing would be inaccessible the clothing will automatically swing to its dependent spaced position.

40 Other objects will appear hereinafter.

The invention is illustrated in the accompanying drawings in which:

Figure 1 is a view in side elevation of the foot portion of the folding bed as disposed 45 when the bed is in its vertical or folded position, showing the manner in which the various articles of bed clothing are suspended in spaced relation to each other. Fig. 2 is a detail view in side elevation showing the 50 parts as arranged when the bed is in its horizontal position illustrating the manner of holding the bed clothing at the foot of the bed against disarrangement. Fig. 3 is a view in perspective illustrating the application of the invention showing the folding bed in its vertical position. Fig. 4 is

a detail in elevation as seen on the line 4—4 of Fig. 1, showing the manner of slidably mounting and engaging the locking bar.

More specifically, 5 indicates the frame of 60 a vertically swinging folding bed having a foot rail 6 mounted thereon and fitted with the usual mattress 7. The foot rail 6 is provided with side rails 8 which connect with the bed frame 5 and may be fitted with intermediate bars as is common in folding bed construction. In carrying out the present invention, a plurality of supporting rods 9 are rigidly mounted on the foot rail in any desired manner and arranged to extend parallel with the side rails 8 at the foot of the mattress 7. The rod 9 is formed with a straight central portion 10 which is adapted to extend horizontally when the bed is in its vertical position and has a downwardly extending hook portion 11 at its inner or lower end preferably disposed adjacent the bed frame 5 and spaced from the outer face of the mattress 7. This hook portion 11 is here shown as comprising a shoulder 12 formed 70 in continuation of the rod 10 extending at right angles thereto which connects with a member 13 extending parallel with the portion 10 and connecting at its outer end with a member 14 which is bent to form a flange 80 15 adapted to be attached to the rail 8 or to the bed frame 5. The outer end of the supporting rod is also formed with a hook member 16 here shown as comprising a shoulder 17 formed in continuation of the member 10 connecting with a member 18 which is bent inwardly at its outer end to form a connecting member 19 having a flange 20 adapted to be attached to the side rail 8 or the foot rail 6. The supporting 90 rod is thus formed with U-shaped depressed portions at each of its ends.

Slidably mounted on each of the supporting rods is a series of rings or loops 21. The rings on each supporting rod are connected together by means of a chain 22 or other flexible member, one end of which is attached to the shoulder 12 or other portion of the supporting rod and the outer end of which connects with a horizontally extending locking bar 23 fitted with loops 24, slidably engaging the supporting rods and arranged to extend transversely across the foot portion of the bed parallel with the foot rail 6, as particularly shown in Fig. 3. The chain 22 is of such length that when the locking bar 23 is positioned in the hook 100 105 110 115

member 16 the chain 22 will be drawn nearly taut with the rings 21 held in spaced relation to each other. Mounted on the rings 21 or connected to the chain 22 adjacent thereto are bed clothing clamps 25 of any suitable construction; corresponding clamps 26 being carried by the locking bar 23 or by the chain 22 adjacent thereto. These clamps 25 may be of any suitable construction and are designed to be detachably engaged with the foot end portions of the various articles of bed clothing, as particularly shown in Figs. 1 and 3.

In the operation of the invention the clamps are secured to the bed clothing in such manner that the innermost article will be suspended on the inner rings 21 carried on each of the supporting rods 9, and the outer article carried adjacent the locking bar 23 with the intermediate articles supported on the intermediate rings 21. When the bed is in a horizontal position the rings 21 and the loops 24 will be engaged by the shoulders 12 of the hook members 11, as illustrated in Fig. 2, and the foot portions of the bed clothing will thereby be securely held against displacement. When it is desired to close the folding bed and to arrange the various articles of bed clothing in spaced relation to each other, the loops 24 of the locking bar 23 and the rings 21 are moved out of engagement with the shoulder 12 and the locking bar is moved upwardly on the members 10 of the supporting rods 35 and the loops 24 thereon engaged with the shoulder 17 of the hook member 16. This may be accomplished while the bed is in its horizontal position whereupon the parts will be disposed as indicated in dotted lines in Fig. 2 or where the bed is folded into a closet and is accessible from its interior the locking bar may be moved to its outermost position when the bed is in its vertical position. On disposing the loops 24 in engagement with the hook member 16 the locking bar 23 will be held against displacement and the chains 22 will be drawn nearly taut so as to dispose the foot portions of the articles of bed clothing in separated relation to each other, and when the bed is swung to its vertical position the various articles of bed clothing will depend from the clamps and be separated from each other so as to permit a free circulation of air therebetween.

Any number of the supporting bars may be mounted on the foot portion of the bed as desired and any number of rings and bed clothes clamps may be provided as occasion requires. It is manifest that any suitable means may be employed for mounting the supporting rods on the bed frame or its foot member other than that here shown, the essential feature being to provide supporting rods with shoulders or depressions by means of which the bed clothes may be held against

displacement either in their separated position when the bed is in its upright position, and held in close contact with each other when the bed is in its horizontal position.

By providing a single locking bar extending transversely of the bed and engaging each of the supporting rods the adjustment of the position of the foot end portions of the articles of bed clothing is facilitated, as in moving the locking bar from one end of the supporting rods to the other the entire collection of articles of bed clothing will be moved therewith. However, in some instances this bar may be dispensed with in which event the outer loops 24 will constitute the locking members which will coöperate with the hooks 11 and 16 in holding the articles of bed clothing in their innermost or outermost positions.

What I claim is:

1. A bed clothes supporting device for folding beds, a plurality of supporting rods carried at one end of the bed frame, shoulders formed at each end of said supporting rods, a plurality of clothes engaging members slidably mounted on said supporting rods, a flexible connection between said slidably clothes engaging members, and means at the outer ends of said flexible connections engageable with said shoulders to retain the bed clothing engaging members either in close or spaced relation to each other.

2. A bed clothes supporting device for vertically swung folding beds comprising a plurality of supporting rods, a series of rings slidably mounted in each of said rods, a flexible connection between the rings on each of the rods, a series of bed clothes engaging clamps on said connections, a locking bar slidably mounted on the supporting rods and connected to the outer end of said flexible connections, and means on said supporting rods for retaining the locking bar in position at either end of the supporting rods.

3. A bed clothes supporting device for vertically swung folding beds comprising a plurality of supporting rods carried by the bed frame, U-shaped hook members formed at each end of each supporting rod, a series of bed clothes clamps slidably mounted on said supporting rods, a locking bar, loops on said locking bar slidable on the supporting rods adapted to be engaged by the U-shaped end portions of the supporting rods, and a flexible connection extending between the clothes clamping members on each of the supporting rods connecting at their outer ends with the locking bar and connecting at their inner ends with the supporting rods.

4. In a bed clothes supporting device for folding beds, a support member carried by the bed, a series of bed clothes engaging

members slidably mounted on said support member, flexible connections between said bed clothes engaging members and hook means formed in each end of said support member adapted to hold the bed clothes engaging members in spaced relation to each other.

5. In a bed clothes supporting device, a supporting rod having spaced dependent hook portions and flexibly connected clothes supporting members slidable on said rod and adapted to be engaged collectively by one of the hook portions and to be spaced

on the rod and held in spaced relation by the other hook portion.

15

6. In a bed clothes supporting device, a supporting rod, a series of flexibly connected clothes supporting members slidably mounted on said rod, a hook on said rod adapted to receive said clothes supporting members, and a second hook on the rod adapted to receive the outermost of the clothes supporting members.

20

In testimony whereof I have signed my name to this specification.

THOMAS SPAULDING.
